[57] CLAIM

The ornamental design for a paper clip holder, as shown and described.

DESCRIPTION

FIG. 1 is a perspective view of the paper clip holder showing my new design;

FIG. 2 is a front elevational view thereof;

FIG. 3 is an elevational view taken from the right side of FIG. 2, the left elevational view being a mirror image;

FIG. 4 is a rear elevational view thereof;

FIG. 5 is a top plan view thereof;

FIG. 6 is a bottom plan view thereof;

FIG. 7 is a perspective view of a second embodiment of the paper clip holder showing my new design;

FIG. 8 is a front elevational view thereof;

FIG. 9 is an elevational view taken from the right side of FIG. 8, the left elevational view being a mirror image thereof;

FIG. 10 is a rear elevational view thereof;

FIG. 11 is a top plan view thereof; and,

FIG. 12 is a bottom plan view thereof.

The broken line shown in FIGS. 1-12 is included for the purpose of illustrating environmental structure only, and forms no part of the claimed design.
